Filed May 21, 1959, Ser. No. 814,719

3 Claims. (Cl. 124—35)

This invention relates generally to the archery art and, more particularly, to a novel and improved archery bow string and arrow drawing and releasing device.

It is an important object of the present invention to provide an archery bow triggering device which is adapted to simultaneously engage the bow string and arrow in a more efficient manner than similar prior art devices and which functions to hold the arrow in the arrow rest of the bow throughout the draw action and up to the time that the arrow is released.

It is another object of the present invention to provide a device of the character described which is adapted to be held in the palm of the hand of the user, whereby the finger and thumb thereon are free to remove an arrow from the user's quiver and place it in the bow in the shooting position and wherein after the release of the arrow, the recoil of the bow cocks the device instantaneously enabling the user to reload the bow without delay.

It is a further object of the present invention to provide a device of the character described which is adapted to grip both the string and arrow during the draw action, whereby the user's pulling ability is increased because of the fact that he may use the power of his full arm to pull back on the bow string, yet which leaves the operator's thumb free to operate the trigger on the device which releases the bow with an instantaneous and smooth action.

It is a still further object of the present invention to provide a device of the character described which is compact and rugged in construction, economical of manufacture, and efficient in operation.

Other objects, features and advantages of this invention will be apparent from the following detailed description and appended claims, reference being had to the accompanying drawing forming a part of the specification wherein like reference numerals designate corresponding parts of the several views.

In the drawings:

Fig. 1 is a fragmentary side view of a bow having the string thereof taut or retracted and releasably engaging the nock of an arrow by means of the improved arrow releasing device;

Fig. 2 is an enlarged side elevational view of the arrow releasing device shown in Fig. 1, and with a part of the device shown in elevational sectional condition;

Fig. 3 is an enlarged elevational sectional view of the structure illustrated in Fig. 2, taken along the line 3—3 thereof and looking in the direction of the arrows;

Fig. 4 is a top plan view of the structure illustrated in Fig. 2; and,

Fig. 5 is a fragmentary enlarged top plan view of the structure illustrated in Fig. 2, and showing the device in an arrow releasing position.

Referring now to the drawings wherein is shown a preferred embodiment of the invention, the numeral 10 indicates a conventional archery bow which includes the

2

usual string 11 secured at its ends to the ends of the bow (not shown) and which is adapted to be drawn rearwardly to a taut position for arrow shooting purposes. A conventional arrow for use with the bow is indicated by the numeral 12. The arrow 12 is provided at the rear end thereof with a nock 13 which is slotted in the usual manner for engagement with the bow string 11.

A preferred embodiment of the present invention is shown in Fig. 1 and in a position wherein it is operatively engaged with the string 11 and arrow 12 preparatory to the releasing of the same. As shown in Figs. 1 and 2, the device of the present invention comprises a body or grip member 14 which is shaped generally like a pistol grip and which is provided with a plurality of finger grip recesses 15 along the inner side thereof. The archery bow trigger of the present invention includes an integral lower arm generally indicated by the numeral 16, and an integral upper arm generally indicated by the numeral 17, between which is pivotally mounted the arm generally indicated by the numeral 18. As shown in Fig. 2, the lower arm 16 comprises the inner horizontal portion 19 which is integral with the grip member 14 and which terminates in the upwardly and outwardly extended portion 20. The lower arm portion 20 terminates in the outer horizontal arm portion 21 upon which is pivotally seated the lower end of the vertical rotatable arm 18. The lower end of the arm 18 is pivotally mounted on the arm portion 21 by means of the bushing 22 which is mounted in the hole 23 and the pivot pin 24 which is threadably mounted in the hole 25 in the lower end of the arm 18.

The upper horizontal arm 17 includes the inner horizontal portion 26 which is integral with the grip member 14 and which is provided with the vertical face 27 on the outer end thereof. Extending outwardly from the inner horizontal arm portion 26 is the outer reduced arm portion 28 which extends outwardly from the upper edge of the inner arm portion 26 and on the under side of which is rotatably seated the vertical arm 18. The upper end of the arm 18 is rotatably mounted on the arm portion 28 by means of the bushing 29 which is seated in the hole 30 in the arm portion 28 and the pivot pin 31 which is threadably mounted in the hole 32 in the upper end of the arm 18.

As shown in Figs. 4 and 5, the upper end of the vertical arm 18 is provided with a quarter-round face 33 which comprises two sides thereof. The vertical arm 18 is adapted to be held in the cocked position shown in Figs. 1 through 4 by means of the following described structure. A tapered hole 34 is formed in the bushing 34a which is mounted in hole 34b formed on the inner side of the arm 18 at the upper end thereof. When the arm is in the cocked position, the tapered hole 34 faces inwardly toward the face 27 of the arm 17. A release pin is generally indicated by the numeral 35 and comprises the rear shaft or rod portion 35a and the enlarged head portion 35b. The release pin 35 is slidably mounted in the stepped hole 36 which extends longitudinally through the arm portion 26. A spring 35c is mounted on the pin 35 behind the head 35b and is seated in the enlarged outer end of hole 36. Spring 35c forces pin 35 into the hole 34 to keep arm 18 in cocked position and trigger 39 locks pin 35 in place. As shown in Fig. 2, the rear end of the release pin 35 abuts the enlarged body portion 38 of the release trigger 39 whereby the pin 35 cannot be moved out of the hole 34.

The trigger 39 is slidably mounted in the vertical hole 40 which is formed in the grip member 14 and which extends downwardly from the upper end of the grip member. A spring 41 is mounted in the lower end of

the hole 40 and engages the lower enlarged end 42 of the trigger 39 and functions to normally bias the trigger upwardly to the position shown in Fig. 2 whereby the release pin 35 is held in a releasably locking engagement in the hole 34. The trigger portions 38 and 42 are connected by the reduced portion 43. The vertical movement of the release trigger 39 is limited by means of the nose 44 on the screw 45 which is threadably mounted in the hole 46 formed on the rear side of the grip member 14. The screw nose 44 extends into the hole 40 opposite the reduced trigger portion 43 and the spring 41 urges the enlarged trigger portion 42 normally upwardly into engagement with the screw nose 44. The trigger 39 further includes the upper reduced portion 47 which extends upwardly from the enlarged portion 38 which terminates in the enlarged head portion 48. The upper end of the hole 40 is enlarged to receive the enlarged trigger head portion 48.

The device of the present invention includes the two arrow and string engaging fingers generally indicated by the numerals 49 and 50, and these fingers are rotatably mounted on one side of the device, as shown in the drawings. The illustrative device is made to be used by a right handed archer and, accordingly, the fingers 49 and 50 are mounted on the left side of the arm 18. It will be understood that a device embodying the principles of the invention could be similarly made for use by a left handed archer, if desired. As shown in Fig. 2, the arm 18 is provided with an inwardly extended concave recess 51 which is centrally longitudinally disposed. Equidistantly disposed on either side of the recess 51 are the fingers 49 and 50 by means of the screws 52 and 53, respectively. The screws 52 and 53 are rotatably mounted in the bushings 54 and 55 which are fixedly mounted in the holes 56 and 58, respectively, in the fingers 49 and 50, respectively. The screws 52 and 53 are threadably mounted in the horizontal holes 59 and 60, respectively. As shown in the drawings, the fingers 49 and 50 are vertically disposed apart and are arcuately formed along the inner side faces thereof, and these inner faces are further provided with the string grooves 61 and 62, respectively. The fingers 49 and 50 are normally biased into the free position shown in Fig. 2 by means of the springs 63 and 64 which are mounted in the grooves 65 and 66 which are formed along the inner faces of the fingers. It will be seen that the outer ends of the springs 63 and 64 engage the pins 67 and 68 which extend outwardly from the arm 18 and into the inner ends of the spring recesses 65 and 66. The outer ends of the springs 63 and 64 engage the outer end of their respective recesses.

The lower side of the upper finger 49 is provided with a straight edge 69 which slopes inwardly and upwardly when the finger is biased to the unloaded position shown in Fig. 2. The outer end of the straight edge 69 is rounded as shown by the numeral 70. The lower finger 50 is provided with a similar straight edge 71 on the upper end thereof which slopes inwardly and downwardly and which terminates in the rounded corner 72. As shown in Figs. 2 and 3, the upper finger 49 is provided with the slot 73 in the lower end thereof which extends inwardly from the outer face to provide a lower flexible gripping portion 75 along the inner edge thereof. The lower finger 50 is provided with a similar slot 74 to provide a similar flexible nose portion 76.

In use, the device of the present invention is carried in the palm of the user whereby the fingers and thumb may still be used to remove an arrow from the quiver and place it in the bow. The device is then placed so

that the string 11 seats in the finger grooves 61 and 62 with the arrow nock between the fingers 49 and 50. The operator then draws back on the grip member 14 whereby the fingers 49 and 50 will be rotated into a gripping engagement with the arrow nock 18, and the arrow will be drawn back simultaneously with the string 11. Due to the slots 73 and 74 formed in the fingers 49 and 50, the nose portions 75 and 76 on the fingers function to provide an efficient grip on the arrow nock yet they are flexible so as to permit an easy and quick release of the arrow. When the user has pulled the arrow 12 back to the desired position, he merely presses downwardly on the trigger head 48 with his thumb to release the arrow. When the trigger 39 is pressed downwardly the pressure on the fingers 49 and 50 of the drawn string 11 will pivot the arm 18 and force the release pin 35 rearwardly into the hole 40 opposite the reduced trigger portion 47. The arm 18 will be pivoted clockwise, when viewed as in Fig. 5, and the spring 11 will roll sidewardly out of the grooves 61 and 62 in the fingers thereby sending the arrow on its way. It will be seen that the device of the present invention permits the user to pull back the arrow string with the full strength of is four fingers whereby the thumb is still free to operate the trigger 39. After the arrow has been released the recoil of the bow string 11 kicks the arm 18 back to the cocked position whereby the device is ready for instant reloading.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

35 What we claim is:

1. A device of the character described, comprising: a grip member having an upper arm and a lower arm extending horizontally outwardly therefrom; a vertically disposed arm pivotally mounted between said upper and lower arms; a pair of spaced apart bow string engaging fingers on one side of said vertical arm in the same vertical plane; said fingers being separately rockably mounted on the vertical arm and being operable to frictionally grip an arrow therebetween when the fingers are engaged by the bow string to draw it taut and cam the fingers against the arrow; and, a trigger operated release means releasably engageable with said vertical arm to hold the same in bow string confining position and operable to release the vertical arm for rocking about its pivot to release the bow string and arrow.

2. The device as described in claim 1, wherein: said fingers are provided with a groove along the inner side thereof for the reception of the bow string; and, the fingers are each provided with a flexible pressure relieving portion on adjacent sides thereof to prevent excess pressure on the arrow nock and any resultant damage thereto.

3. The device as described in claim 1, wherein: said trigger operated release means includes a release pin releasably engageable with said vertical arm, and, a manually operable spring biased trigger adapted to normally retain said release pin in engagement with said vertical arm.
